UNITED STATES PATENT OFFICE.

ERNEST HUTTON, OF WAYLAND, KENTUCKY.

FIRING-TERMINAL OF BLASTING-GUNS.

1,252,119.

Specification of Letters Patent.

Patented Jan. 1, 1918.

Application filed March 28, 1917. Serial No. 158,076.

To all whom it may concern:

Be it known that I, ERNEST HUTTON, a citizen of the United States, residing at Wayland, in the county of Floyd and State 5 of Kentucky, have invented certain new and useful Improvements in Firing-Terminals for Blasting-Guns, of which the following is a specification.

This invention relates to that class of 10 blasting devices that are arranged to carry an explosive charge at one end, to push the charge to the desired place in a bored hole, and to fire the charge.

It is an object of the invention to provide 15 for a blasting-gun of this type a charge holding and firing terminal of improved construction that is adapted to be inserted into the end of the cartridge-casing and thereby to hold the charge, that is reliable 20 in performing the firing function, that may be cleaned easily, and that is readily removable from the gun for purposes of cleaning and repair of the parts.

When read in connection with the description herein, the details of construction and arrangement of parts contemplated by the invention will be apparent from the accompanying drawing, forming part hereof, wherein an embodiment of the invention is 30 disclosed, for purposes of illustration.

While the disclosures herein now are considered to exemplify a preferable embodiment of the invention, it is to be understood that it is not the intention to be limited 35 necessarily thereto in interpretation of the claims, as modifications within the limits of the claims can be made without departing from the nature and spirit of the invention.

Like reference-characters refer to corresponding parts in the views of the drawing, 40 of which—

Figure 1 is a plan view;

Fig. 2 is a longitudinal sectional view on the line 2—2, Fig. 1; and

Fig. 3 is an end view of the bushing.

Having more particular reference to the drawing, 4 designates the end portion of the barrel or rod of a blasting-gun, which is formed with a concentric screw-threaded circular recess 5 opening to its end to receive a portion of the firing member.

The device includes a peripherally screw-threaded disk 6 screwed into the recess 5 to its inner end. The disk has integrally 55 formed therewith and extending from its outer face a tapered or trunco-conically

shaped bushing formed of contractible fingers 7, the fingers being produced by cutting slots 8 longitudinally in the bushing from its free end to the disk, which latter is the 60 base of the bushing. A bore or passage 9 extends axially through the disk and bushing.

The firing member proper has an annular shoulder 10 arranged to abut the end of the 65 barrel or rod of the gun, and extending inwardly from this shoulder there is a smaller exteriorly screw-threaded ring portion 11 arranged to be screwed into the recess 5 with its end abutting the disk 6. A flattened dia- 70 metrically-disposed portion 12, constituting a firing-pin, extends outwardly from the shoulder 10, it is formed with an opening 13 extending laterally therethrough from one flattened face to the other, and it is some- 75 what pointed at its free end 14. The material is gradually reduced in thickness by a groove 15 formed in each of the flattened faces from the pointed end to the edge of the opening 13, whereby there is provided a 80 somewhat pointed centrally-disposed rearwardly-extending spark-terminal 16.

The member is hollow from its threaded or inner end 11 to the opening 13, whereby there is provided a passage 17 that is concentric with the bore 9 of the bushing. The passage or bore 17 at its inner end portion is of funnel shape, or gradually reduces in size toward the opening 13, as shown at 18, and it conforms approximately to the exterior 90 contour of the bushing formed by the fingers 7, so that, when the ring portion 11 is screwed into the recess 5 toward the disk 6, the fingers are contracted toward one another.

Of an electric circuit including a battery or other suitable source of electricity and a switch, one wire is grounded in the barrel or rod of the gun (these parts not being shown), and the other wire 19 of the circuit 100 is insulated and leads through the barrel or rod to the inner or firing end thereof, as is of common practice in the art. The wire further leads through the opening in the bushing, wherein it is held tightly by the 105 contracted fingers 7 gripping the insulation, and it extends from the passage of the firing member to the opening 13 thereof, where its free end constitutes an uninsulated spark terminal 20 that is directly opposite to the 110 terminal 16.

When a gun of which the device is a part

is to be used, an explosive cartridge, such as shown by dotted lines in Fig. 1 and designated by A, is placed and held on the device by its flattened and pointed end being forced into the end of the cartridge, and the latter is pushed by the gun to the bottom or inner portion of the hole in which it is to be fired. During insertion of the device into a cartridge, or into explosive that previously may have been placed in the hole if that method is followed, the terminal 20 of the wire is protected by the material of the device on the opposite side of the opening, and thus liability of grounding of the terminal is obviated. Some of the explosive takes position in the opening 13.

Thereafter, the switch of the electric circuit is closed and a spark thereby is caused to jump across the space between the terminal points 16 and 20, the latter of which is connected with the other wire of the circuit by that wire being grounded in the barrel or rod of the gun. This explodes the charge.

The spark-points 16 and 20, by reason of that particular disposition in the opening 13, are accessible easily for cleaning. Moreover, if through successive use the wire-terminal 20 becomes burnt, worn, or broken off, the firing member may be unscrewed from the recess 5 and the grip of the fingers 7 on the insulation of the wire 19 thereby loosened. Then more wire may be drawn from the gun and insulation removed from its end, whereby a new terminal is provided, after which the firing member again may be screwed into place and the fingers thereby caused again to grip the wire-insulation.

Having thus described my invention, what I claim as new, and desire to secure by Letters Patent, is—

1. A firing member for blasting-guns having a flattened free end portion adapted to

be inserted into an explosive charge and having an opening extending therethrough 45 in the line of its lesser dimension, there being oppositely-disposed grooves in said end portion leading to said opening in gradually increasing depth whereby a spark-point is provided at the edge of the opening. 50

2. A firing device adapted to be attached at one end to a blasting-gun, having for accommodation of an electric conductor a longitudinal passage formed with a converging wall, and a member having contractible exteriorly tapered fingers arranged to extend into said passage and to be pressed by the converging wall thereof against and to hold the conductor. 55

3. A firing device adapted to be attached at one end to a blasting-gun, formed in its outer portion with a transverse opening, and having a passage leading to said opening formed with a converging wall, and a member having contractible exteriorly tapered 65 fingers arranged to extend into said passage and to be pressed by the converging wall thereof against an electric conductor leading to said opening.

4. The combination, with a blasting-gun 70 having a screw-threaded recess in its end, of a firing device comprising a member in said recess having contractible exteriorly tapered fingers extending outwardly therefrom, and a firing member screwed at one 75 end into said recess and having a transverse opening in its outer portion and a passage extending from the inner end to said opening, said passage having a tapered portion arranged to receive said fingers and to press 80 them toward one another, and an electric conductor held between said fingers and extending to said opening.

In testimony whereof, I affix my signature.

ERNEST HUTTON.
